UNITED STATES PATENT OFFICE.

JOHN J. PARKER, OF AITKIN, MINNESOTA, ASSIGNOR TO W. W. PARKER, OF SPEARFISH, DAKOTA TERRITORY.

DESIGN FOR A SAW-BLADE.

SPECIFICATION forming part of Design No. 16,869, dated August 24, 1886.

Application filed July 14, 1886. Serial No. 208,045. Term of patent 7 years.

To all whom it may concern:

Be it known that I, JOHN J. PARKER, a citizen of the United States, residing at Aitkin, in the county of Aitkin and State of Minnesota, have invented certain new Designs for Saws; and I do declare the following to be a full, clear, and exact description of the invention, such as will enable others skilled in the art to which it appertains to make and use the same, reference being had to the accompanying drawing, and to the letters and figures of reference marked thereon, which form a part of this specification.

The figure is a side elevation of my newly designed saw, only a section being illustrated.

The important features of my design are, first, that the edges of the scoring-teeth and of the planer-teeth are arranged at uniform angles; second, the scoring-teeth are arranged on different angles in the saw.

A designates the saw, *a* the planer-teeth, and *b* the scorer-teeth. The edges *b' b'* of the teeth *b* are at an angle from each other equal to the angles which exist between the edges *a' a'* of the teeth *a*; but adjacent edges of teeth *a*

and teeth *b* are parallel with each other—that is to say, the edges *a' b'* are parallel and terminate in a curve, *c*.

I claim—

1. The design for a saw-blade, as described and shown, the same consisting of the saw-blade having upon one edge teeth *b*, with their edges *b' b'* arranged at angles equidistant from a vertical line, and teeth *a*, having their edges *a' a'* parallel with the edges *b' b'* of the teeth *b* and their edges *a' a'* but slightly removed from a horizontal, as set forth.

2. The design for a saw-blade, as shown and described, the same consisting of the blade *A*, having upon one edge teeth *a* and teeth *b*, the teeth-edges *b' a'* being parallel and terminating in a curve *c* in the body of the saw-blade, as set forth.

In testimony whereof I affix my signature in presence of two witnesses.

JOHN J. PARKER.
